UNITED STATES PATENT OFFICE.

EUGENE A. SISSON, OF WORCESTER, MASSACHUSETTS, ASSIGNOR TO UNIVERSAL PATENTS COMPANY, OF WOONSOCKET, RHODE ISLAND, A CORPORATION OF RHODE ISLAND.

WOVEN CARRIER.

1,286,814.

Specification of Letters Patent.

Patented Dec. 3, 1918.

Application filed July 9, 1917. Serial No. 179,349.

To all whom it may concern:

Be it known that I, EUGENE A. SISSON, a citizen of the United States, residing at Worcester, in the county of Worcester, State 5 of Massachusetts, have invented a certain new and useful Improvement in Woven Carriers, of which the following is a specification, reference being had therein to the accompanying drawings.

10 The invention has relation to pocketed carriers made of woven material, on the order of those which are used for holding and carrying cartridges, packaged first-aid supplies, etc.

15 The invention is applicable in the manufacture of cartridge-carriers, hospital corps belts, medical officers' belts, and other carriers having various special adaptations.

20 A carrier of the class to which the invention relates is made ordinarily in the form of a belt, or of a section of a belt, the belt or respective belt sections comprising a supporting-band, a plurality of pockets which project from said band, and, usually, pocket-25 covers or flaps which are connected flexibly with the band.

25 The invention consists in a carrier of novel and improved construction made up of parts which are composed of pieces of woven material that are fastened together to give them the required form and unite them.

30 Illustrative embodiments of the invention are shown in the drawings, in which latter,—

35 Figure 1 is a view on the order of a perspective view showing a portion of a carrier and representing one of the said embodiments.

40 Fig. 2 is a view of a blank such as is used in making one of the pockets shown in Fig. 1.

45 Figs. 3, 4, and 5 show modifications in the construction of the supporting-band.

50 Figs. 6 and 7 show modified reinforcements for the lower margin of the supporting band.

45 Fig. 8 is a sectional detail view.

Having reference to the drawings,—the supporting-band in Fig. 1 has its opposite faces constituted at separate thicknesses 1, 1^a, of woven material. The separately-formed pockets 2, 2, one of which is mostly broken away in Fig. 1, are mounted upon the face 1^a. The supporting-band is strengthened along its lower margin by means of a longitudinally-extending reinforce 55 force 3. The bottom line of eyelets 4, 4, de-

signed to receive the hooks of hangers, etc., for the suspension of various supplemental pieces of equipment are set in this reinforced portion of the band. The reinforcement provides for the better holding of the eyelets, and protects the said marginal portion from giving way or tearing under the strain that is applied at the eyelets.

To provide a housing-slit for the reception of the rearward attaching extensions 5^a, 5^a, of the pocket-covers or flaps 5, 5 the top marginal portions 1^b, 1^b, of the different thicknesses composing the upper portion of such band are secured together along a line 6 that is located at a short distance below the top 70 of the band. Prior to the application of the pocket-covers or flaps the said top marginal portions 1^b, 1^b, are not connected together above the line 6, and they are capable of being opened away from each other as far 75 down as such line for the reception of such extensions between them. The bottom of the said housing-slit adjoining the line of fastening 6 serves as a stop which limits the depth to which the extensions may be inserted 80 into the housing-slit in assembling the covers or flaps in connection with the band, and which also assists in keeping the covers or flaps in proper positions relative to the band until and while the said top marginal 85 portions 1^b, 1^b, and the extensions 5^a, 5^a, between them are secured together by a line of fastenings 7.

In the preferred construction shown by Fig. 1 of the drawings, the supporting-band 90 is made of a piece of woven material having a width a little more than twice that of a completed band from top to bottom. This piece is doubled upon itself along a longitudinal line, thereby producing a fold at the 95 bottom of the band and bringing the two thicknesses 1, 1^a, together. The reinforce 3 is a narrow strip of woven material which is inclosed between the two thicknesses adjacent the said fold. The margin in which the 100 bottom eyelets 4, 4, are set is stronger because of the fold. The latter incloses and conceals the adjoining edge of the reinforce, and gives a smooth finish to the lower edge of the supporting-band. The top margins of the 105 two thicknesses 1, 1^a, are inturned so as to reinforce the top of the band, produce a smooth finish, and hide the cut edges. The lines of fastenings 6 and 7 are stitches.

While it is preferred that the reinforce 110

strip should be inclosed between the two thicknesses 1, 1^a, the reinforce may be externally applied, as at 3^e, Fig. 6, if deemed advisable, or if that be more convenient in practice in the case of some particular construction of carrier. Fig. 3 show a reinforce which is an integral portion of the band, it being constituted by an infold of the lower portion of the latter, and being secured by a line of stitches 3^a.

In some cases the thicknesses of woven material constituting the different faces of the supporting-band may consist of separate pieces of such material fitted together, as in Figs. 4 and 5. In Fig. 4 two selvaged webs 1^c, 1^c, are shown, with the reinforce strip 3^c confined between their lower marginal portions. In this case, the upper margins do not have to be inturned. Fig. 5 shows two pieces 1^d, 1^d, cut from a large web, both having the raw or cut top and bottom margins thereof inturned. A separate reinforce strip may be employed in the construction of Fig. 5, as at 3^c, Fig. 7, but in Fig. 5 a separate strip is omitted, and the reinforce is constituted by the inturned portions 3^d, 3^d, at the bottoms of the two pieces 1^d, 1^d.

In some cases, other approved fastenings or means of connecting the various thicknesses together may be substituted for the stitches of the lines 6, 7, but stitches are preferred.

The pockets may be, in general, variously made and attached to the supporting-band. The drawings show pockets embodying certain improvements constituting the invention that is covered by the divisional application filed October 23, 1917, Serial No. 198,048. The blank shown in Fig. 2 is employed in making such pocket. The said blank is substantially T-shaped, it having the two opposite wing-portions 2^b, 2^b, which are adapted to constitute the lateral portions or sides of the pocket, and the intermediately projecting portion 2^d adapted to constitute the front of the pocket. The side-portions and front portions are bent upward at right angles to the central portion 2^e, which constitutes the bottom of the pocket, and the overlapping margins of the said sides and front are secured together by vertical seams 2^f, at the angles between the side and front. The front margins of the sides 2^b, 2^b, are inturned to conceal and protect their raw or cut edges. The top of the pocket is bound with a tape 2^g which incloses and conceals the raw or cut top edges of the sides and front, and gives a smooth finish. The rear margins of the sides and bottom are doubled upon themselves to turn inward the raw or cut edges thereof, and after the doubled margins have been outturned against the surface of the face 1^a of the supporting-band the pocket is attached to the supporting-band, by 65 stitches 8, or other approved fastenings,

passing through the said outturned margins or flanges and the supporting-band.

Fastenings of approved character usually will be provided for preventing accidental opening of the pocket-covers or flaps. Fig. 70 shows coacting members 9, 10, of devices of the glove-fastener type.

What is claimed is:—

1. A carrier comprising one or more pockets and one or more pocket-covers or flaps, and a made-up supporting band having the opposite faces thereof composed of separate thicknesses of woven material equal or substantially equal in width to the body-portion of said supporting-band brought into juxtaposition and fastened together by a line of applied fastening means at a distance from the top edge of the band so as to produce a housing-slit and also produce adjacent the line of fastenings a bottoming stop which limits the entrance of the rearward attaching extension or extensions of the pocket-cover or covers into the housing-slit and positions the cover or covers, with the sides of the housing-slit and the interposed extension or extensions secured together by fastenings.

2. A carrier comprising one or more pockets and one or more pocket-covers or flaps, and a supporting-band having the opposite faces thereof composed of separate thicknesses of woven material equal or substantially equal in width to the body-portion of said supporting-band brought into juxtaposition and fastened together by a line of stitches at a distance from the top edge of the band so as to produce a housing-slit and a bottoming-stop for the rearward attaching extension or extensions of the cover or covers, with the sides of the housing-slit and the interposed extension or extensions fastened together.

3. A carrier comprising one or more pockets and one or more pocket-covers or flaps, and a supporting-band composed of a piece of woven material folded upon itself lengthwise of the carrier, having its juxtaposed portions fastened together along a line at a distance from the top edge of the band so as to produce a housing-slit and a bottoming-stop for the rearward attaching extension or extensions of the cover or covers, with the sides of the housing-slit and the interposed extension or extensions fastened together.

4. A carrier comprising one or more pockets and one or more pocket-covers or flaps, and a supporting-band composed of a piece of woven material folded upon itself lengthwise of the carrier, having its juxtaposed portions fastened together by a line of stitches at a distance from the top edge of the band so as to produce a housing-slit and a bottoming-stop for the rearward attaching extension or extensions of the cover

or covers, with the sides of the housing-slit and the interposed extension or extensions fastened together.

5. A carrier comprising one or more 5 pockets and one or more pocket-covers or flaps, and a made-up supporting-band having the opposite faces thereof composed of separate thicknesses of woven material brought into juxtaposition, reinforced along 10 the lower margin, with eyelets set in the reinforced portion, and fastened together by applied fastening means along a line at a distance from the top edge of the band so as to produce a housing-slit and a bottoming stop for the rearward attaching extension or extensions of the cover or covers, with the sides of the housing-slit and the interposed extension or extensions fastened together.

6. A carrier comprising one or more 20 pockets and one or more pocket-covers or flaps, and a supporting-band having the opposite faces thereof composed of separate thicknesses of woven material brought into juxtaposition, reinforced along the lower 25 margin, with eyelets set in the reinforced portion, and fastened together by a line of stitches at a distance from the top edge of the band so as to produce a housing-slit and a bottoming-stop for the rearward attaching 30 extension or extensions of the cover or covers, with the sides of the housing-slit and the interposed extension or extensions fastened together.

7. A carrier comprising one or more 35 pockets and one or more pocket-covers or flaps, and a supporting-band composed of a piece of woven material folded upon itself lengthwise of the carrier, reinforced along the lower margin, with eyelets set in the reinforced 40 portion, having its juxtaposed portions fastened together along a line at a distance from the top edge of the band so as to produce a housing-slit and a bottoming-stop for the rearward attaching extension or 45 extension or extensions of the cover or covers, with the sides of the housing-slit and the interposed extension or extensions fastened together.

8. A carrier comprising one or more 50 pockets and one or more pocket-covers or

flaps, and a supporting-band composed of a piece of woven material folded upon itself lengthwise of the carrier, reinforced along the lower margin, with eyelets set in the reinforced portion, having its juxtaposed 55 portions fastened together by a line of stitches at a distance from the top edge of the band so as to produce a housing-slit and a bottoming-stop for the rearward attaching extension or extensions of the cover or 60 covers, with the sides of the housing-slit and the interposed extension or extensions fastened together.

9. A carrier comprising one or more pockets and one or more pocket-covers or flaps, 65 and a supporting-band composed of a piece of woven material folded upon itself lengthwise of the carrier, and reinforced by a reinforce inclosed within the fold, and with eyelets set in the reinforced portion, and having its juxtaposed portions fastened together along a line at a distance from the top edge of the band so as to produce a housing-slit and a bottoming-stop for the rearward attaching extension or extensions 75 of the cover or covers, with the sides of the housing-slit and the interposed extension or extensions fastened together.

10. A carrier comprising one or more pockets and one or more pocket-covers or 80 flaps, and a supporting-band composed of a piece of woven material folded upon itself lengthwise of the carrier, and reinforced by a reinforce inclosed within the fold, and with eyelets set in the reinforced portion, 85 having its juxtaposed portions fastened together by a line of stitches at a distance from the top edge of the band so as to produce a housing-slit and a bottoming-stop for the rearward attaching extension or extensions of the cover or covers, with the sides of the housing-slit and the interposed extension or 90 extensions fastened together.

In testimony whereof I affix my signature in presence of two witnesses.

EUGENE A. SISSON.
